Primary Examiner—James R. Largen

[57] CLAIM

The ornamental design for a toilet seat positioning handle, as shown and described.

DESCRIPTION

FIG. 1 is a top perspective view of a toilet seat positioning handle showing my new design;

FIG. 2 is a top plan view thereof;

FIG. 3 is a bottom plan view thereof;

FIG. 4 is a rear elevational view thereof; and,

FIG. 5 is a right side elevational view thereof, the left side being a mirror image of the right side.
